UNITED STATES PATENT OFFICE.

WILLIAM T. SMITH, OF PHILADELPHIA, PENNSYLVANIA.

WOVEN FABRIC.

SPECIFICATION forming part of Letters Patent No. 707,871, dated August 26, 1902.

Application filed February 17, 1902. Serial No. 94,464. (No specimens.)

To all whom it may concern:

Be it known that I, WILLIAM T. SMITH, a citizen of the United States, residing in Philadelphia, Pennsylvania, have invented certain 5 Improvements in Woven Fabrics, of which the following is a specification.

My invention relates to that class of woven fabrics in which are combined party-colored face weft-threads, back weft-threads of spun 10 yarn, stuffer warp-threads separating the face and back weft-threads, and binder warp-threads tying together said face and back weft-threads, the object of my invention being to produce a fabric of this character having 15 on the face a pattern formed by party-colored chenille weft-threads and on the back a pattern in imitation of matting and formed by the back weft-threads beaten up so closely as to prevent any showing of the chenille face 20 weft-threads between them and presenting either a plain face or one having stripes of color across the same produced by the binding warp-threads.

In the accompanying drawings, Figure 1 is 25 an exaggerated section taken in the direction of the warp of a fabric produced in accordance with my invention; and Fig. 2 is a view of a portion of the back of the fabric, illustrating the striped effect before referred to.

30 The fabric is composed of face weft-threads 1 of party-colored chenille, back weft-threads 2 of spun yarn, stuffer warp-threads 3 interposed between the face weft-threads and back weft-threads, and binder warp-threads 4, 35 which serve to tie the face and back weft-threads together and confine the stuffer warp-threads between them. The back weft-threads are of such size and are beaten up so closely that the chenille face weft-threads are not visible 40 between them. Hence these back weft-threads impart to the back of the fabric a color or tint which may remain plain, but which I prefer to modify by using binding warp-threads of colors differing from each other 45 and from the color of the back weft-threads, thereby producing upon the back of the fabric the effect of stripes running in the direction of the warp. I thus impart to the back of the fabric a matting effect which renders the 50 fabric reversible, either face of the same being acceptable.

Binding warp-threads of the thickness nec-

essary to produce a striping effect upon the back of the fabric can be used without affecting the face pattern, owing to the fact that 55 on the face of the fabric said warp-threads are covered and hidden by the chenille fur of the face weft-threads 1, and yet these heavy binding warp-threads will not prevent close beating up of the back weft-thread, sowing to 60 the fact that the latter are large and soft, and hence close around the binding warp-threads.

It will of course be understood that the drawings for the purpose of clearer illustration show the weft-threads in a loose and 65 open condition and not as they appear when beaten up.

Having thus described my invention, I claim and desire to secure by Letters Patent—

70 1. A woven fabric composed of party-colored chenille face weft-threads, back weft-threads of spun yarn, and binding warp-threads uniting the face and back weft-threads, said back weft-threads being large and soft whereby 75 they can be beaten up so closely as to prevent any showing of chenille threads on the back of the fabric, thereby imparting to the latter a matting effect, substantially as specified.

80 2. A woven fabric composed of party-colored chenille face weft-threads, back weft-threads of spun yarn, beaten up so closely as to prevent any showing of chenille threads on the back of the fabric and binding warp-threads 85 uniting the face and back weft-threads, said binding warp-threads being covered and hidden by the chenille fur of the face weft-threads and being of color or colors differing from and contrasting with that of the back 90 weft-threads, whereby a striped effect upon the back of the fabric is produced, substantially as specified.

95 3. A woven fabric composed of party-colored chenille face weft-threads, back weft-threads of spun yarn, stuffer warp-threads separating the face and back weft-threads, and binding warp-threads uniting the face and back weft-threads, said back weft-threads being large and soft whereby they can be beaten 100 up so closely as to prevent any showing of chenille threads on the back of the fabric, thereby imparting to the latter a matting effect, substantially as specified.

4. A woven fabric composed of party-colored chenille face weft-threads, back weft-threads of spun yarn beaten up so closely as to prevent any showing of chenille threads on the back of the fabric, stuffer warp-threads separating the face and back weft-threads, and binding warp-threads uniting the face and back weft-threads, said binding warp-threads being covered and hidden by the chenille fur of the face weft-threads and being of color or colors differing from and contrasting with

that of the back weft-threads whereby a striped effect upon the back of the fabric is produced, substantially as specified.

In testimony whereof I have signed my ¹⁵ name to this specification in the presence of two subscribing witnesses.

WILLIAM T. SMITH.
